(57) **CLAIM**

The ornamental design for a beverage glass, as shown and described.

DESCRIPTION

2.-5. Beverage glass

2.1 - bottom perspective view of a first embodiment of a beverage glass;

2.2 - Front elevational view;

2.3 - Rear elevational view;

2.4 - Left side elevational view;

2.5 - Right side elevational view;

2.6 - Top plan view;

2.7 - Bottom plan view;

3.1 - bottom perspective view of a second embodiment of a beverage glass;

3.2 - Front, side and rear elevational view;

3.3 - Top plan view;

3.4 - Bottom plan view;

4.1 - bottom perspective view of a third embodiment of a beverage glass;

4.2 - Front elevational view;

4.3 - Rear elevational view;

4.4 - Left side elevational view;

4.5 - Right side elevational view;

4.6 - Top plan view;

4.7 - Bottom plan view;

5.1 - bottom perspective view of a fourth embodiment of a beverage glass;

5.2 - Front, side and rear elevational view;

5.3 - Top plan view; and

5.4 - Bottom plan view.
